FIG. 3

UNITED STATES PATENT OFFICE.

ROBERT W. PAIN, OF NEW YORK, N. Y., ASSIGNOR TO THE AEOLIAN COMPANY,
A CORPORATION OF CONNECTICUT.

FOLDING PEDAL.

No. 869,980.

Specification of Letters Patent.

Patented Nov. 5, 1907.

Application filed June 28, 1907. Serial No. 381,190.

To all whom it may concern:

Be it known that I, ROBERT W. PAIN, a citizen of the United States, and resident of the borough of Manhattan, city, county, and State of New York, have invented 5 certain new and useful Improvements in Folding Pedals, of which the following is a specification.

This invention relates to a folding pedal attachment for use in connection with mechanical musical instruments, organs, &c.

10 The object of the invention is to so arrange the bellows-actuating pedal that the movement of a door which closes an opening in the front of the case, shall bring the pedal out of the case into position for action, and restore the same to its position within the casing.

15 This object I attain by the construction illustrated in the following drawings:

Figure 1 is a sectional elevation showing the apparatus with the door closed. Fig. 2 is a sectional elevation showing the position of the pedal after it has been 20 withdrawn from the casing and in position for use. Fig. 3 is a rear view of the pedal in the position shown in Fig. 1.

The front portion A of the casing has an opening therein, which is closed by a door B having a handle b; this 25 door B having hinged to its bottom a lifting bar or block C. The lifting block is provided at its outer edges with projections or tenons adapted to slide in grooves D, which are provided in guiding pieces E located at each side of the door opening. The lifting blocks have 30 secured thereto ears F on which are mounted outwardly projecting pins G.

Rearwardly of the door and within the casing are pivoted a pair of pedal-rest arms H. These arms have secured to their ends a pedal rest I, the arms being of such 35 length that when swung forward the pedal rest I will rest upon the floor in front of the casing of the instrument. Pivoted at one end to this pedal rest bar are the 40 pedals J, which have near their other ends ears K, to which are pivotally connected the links L which operate the bellows (not shown).

The pedal-rest arms H are provided with forwardly projecting lugs M to which are pivoted a pair of lifting links N, connected at their upper ends by a link connecting rod O. These rest arms H are also provided 45 with rearwardly projecting arms m having at their ends inturned and perforate flanges o. The lifting links N have secured about midway of their length a perforated lug n. A coiled rod p has its two ends passed through the perforated lugs n and o, this coiled rod serving as a 50 spring tending to maintain the lifting links N in their forward position.

Near the outer end of each lifting link N is provided a 55 notch P adapted to engage with the lifting pin G when the door and its lifting bar are raised to their highest position, as shown in dotted lines in Fig. 1.

The guide pieces E have at their upper ends a pair of lugs or ears Q, serving as bearings for a rock-shaft R, to which are secured two link-release fingers S. To the end of the rock-shaft is secured an arm or crank T, having pivoted to its outer end a rod U sliding in guides V 60 secured to the back of the casing. To the upper guide V is attached a spiral spring W, which at its other end is connected to the crank T. Arranged to bear on the upper end of the rod is a lever X pivoted on an ear secured to the framework.

65 The operation of the device is as follows:—The door B is first swung outwardly and then raised, the blocks C sliding in their guides until the door reaches its topmost position. At this point the pins G will drop into the notches P in the lifting links N. By then allowing the 70 door to move downward the links N will also move downwardly and cause the rest arms H to swing forwardly about their pivots, bringing the pedals J out through the opening in the casing, the movement continuing until the pedal rest I reaches the floor in the position shown in Fig. 2. To restore the pedal to its position within the casing, the door is again raised to its highest position, when, by operating the lever X, the fingers S on the rock-shaft will engage the cross-bar O, and force 75 notches P on the lifting links N out of engagement with the lifting pins G, thereby permitting the door to be lowered into its original position, while the bar O rests against the release fingers S and supports the pedal mechanism in its upright position within the casing. Suitable means may be provided for keeping the door 80 closed and for sustaining it when in its raised position.

I claim:

1. In a musical instrument, the combination of a casing, a door in the casing, a swinging support, a pedal mechanism mounted thereon, and means connecting the door and support, whereby the movement of the door causes the 90 pedal mechanism to swing in and out of the casing.

2. In a musical instrument, the combination of a casing, a door in the casing, a swinging support, a pedal mechanism mounted thereon, and means detachably connecting 95 the door and support, whereby the movement of the door causes the pedal mechanism to swing in and out of the casing.

3. In a musical instrument, the combination of a casing, a door in the casing, a swinging support, a pedal mechanism mounted thereon, guides on the casing, a lifting bar hinged to the door and arranged to slide on the casing, and means for connecting the lifting bar to the 100 swinging pedal support.

4. In a musical instrument, the combination of a casing, a door in the casing, a swinging support, a pedal mechanism mounted thereon, guides on the casing, a lifting bar hinged to the door and arranged to slide on the casing, and means for detachably connecting the lifting bar to the 105 swinging pedal support.

5. In a musical instrument, the combination of a casing, a door in the casing, a swinging support, a pedal mechanism mounted thereon, guides on the casing, a lifting bar hinged to the door and arranged to slide on the casing, and means for detachably connecting the lifting bar to the 110 115

swinging pedal support, comprising pins on the bar, co-operating notches on the swinging support, and means for disengaging the pins from the notches.

6. In a musical instrument, the combination of a swinging support, a pedal mechanism pivotally mounted thereon, a pivoted link connected to the support, raising and lowering mechanism and means for detachably connecting

a pedal mechanism having a pair of pivoted pedal rest arms, pedal rests secured to the ends of such arms and a pedal pivoted thereto, the pedal rest arms having pivoted thereto a spring controlled lifting link having a notch in its end, a door in the casing arranged to be raised and lowered, lifting pins carried by the door and adapted to engage the notches in the lifting links, and a lever mech-

20

the link with the raising and lowering mechanism.

7. In a musical instrument, the combination of a swinging support, a pedal mechanism pivotally mounted thereon, a pivoted link connected to the support, a spring arranged to press said link outwardly, raising and lowering mechanism and means for detachably connecting the link with the raising and lowering mechanism.

15 8. In a musical instrument, the combination of a casing,

anism for disengaging the links from the pins.

In testimony whereof I have signed this specification in the presence of two subscribing witnesses.

ROBERT W. PAIN.
